UNITED STATES PATENT OFFICE.

LEONARD BRICKER, OF SPRINGFIELD, ILLINOIS.

COMBINATION OF SMOOTHING-IRON AND LAMP.

Specification of Letters Patent No. 29,949, dated September 11, 1860.

To all whom it may concern:

Be it known that I, LEONARD BRICKER, of Springfield, county of Sangamon, and State of Illinois, have invented a new and improved lamp designed to heat rotary or revolving smoothing-irons, together with an improved mode of attaching said lamp to said irons.

To enable others skilled in the art to make and use my invention I will describe it more fully.

I construct my irons in any of the known forms of the rotary or two faced smoothing irons and then I make my lamp in any desirable form and construct the tube in such a form that the end of the wick will be as high as the top of the fluid in the body of the lamp, the object to be attained being the use of a loose wick and thus avoid the great inconvenience of using the tight wick necessary in a lamp of any other form for the purpose described, and then I connect the lamp with the iron by a neatly formed dove-

tail the lips or flanges of which are cast on the iron and the wedge on the lamp or vice versa as shown in the drawings.

Figure 1, is a side elevation of the iron and lamp combined A A represents the dovetail and B the tube and C, C, a guard to prevent the tube from heating by the flame of the lamp. Fig. 2, represents a rear elevation of the iron showing the manner of attaching the flanges thereon. Fig. 3, is a side elevation of the lamp showing the tube and dovetail &c.

35

What I claim as my invention and desire to secure by Letters Patent is—

The arrangement and combination of the lamp with elevated tube B, and guard C, C; dovetail A, A, and smoothing iron, all in 40 the manner and for the purpose herein described.

LEONARD BRICKER.
